US00D574701S

(12) **United States Design Patent**
Clarke

(10) **Patent No.:** US D574,701 S
(45) **Date of Patent:** ** Aug. 12, 2008

(54) **LOCKING DEVICE FOR WIRE ROPE
SUSPENSIONS**

(75) Inventor: **Neil Clarke**, Sheffield (GB)

(73) Assignee: **Gripple Limited**, Sheffield (GB)

(**) Term: **14 Years**

(21) Appl. No.: **29/295,362**

(22) Filed: **Sep. 27, 2007**

(51) **LOC (8) Cl. 08-08**

(52) **U.S. Cl. D8/383**

(58) **Field of Classification Search** D8/383,
D8/333, 395; D11/215, 212; 24/115 G,
24/115 M, 115 R

(57) **CLAIM**

The design for a locking device for wire rope suspensions, as shown and described.

DESCRIPTION

FIG. 1 is front, perspective view of the locking device;

FIG. 2 is a view of the rear;

FIG. 3 is a view of the left side;

FIG. 4 is a view of the right side;

FIG. 5 is a view of the top; and,

FIG. 6 is a view of the bottom.
